COMPRESSED GAS OPERATED HARPOON GUN
John George Houghton, 245 Camden Road,
Parsippany, N.J. 07054
Filed Sept. 27, 1965, Ser. No. 495,020
17 Claims. (Cl. 124—15)

This specification is a continuation-in-part of my application Ser. No. 287,340 filed June 12, 1963, and now abandoned.

This invention relates to spear guns and more particularly to manually operable guns such as are used for underwater spear fishing.

Even more particularly this invention relates to spear guns of the pneumatic and hydro-pneumatic type and in particular to a spear gun which is convertible from pneumatic to hydro-pneumatic operation and back again as is shown in one embodiment of my invention in which I provide a gun whose chamber is adapted to be hydraulically charged or be operable solely as a compressed air propulsive gun.

Manually operated spear guns heretofore used for underwater spear fishing have generally used bands, spring mechanisms, pneumatic or hydro-pneumatic as the propelling means for the spear. In each case the firing force is generally obtained by manually inserting the spears in the guns to stress the elastic bands or springs or to compress the air. The characteristics and limitations of the spring and rubber types being generally known, only the hydro-pneumatic and pneumatic types will herein be discussed.

The pneumatic spear gun which utilizes a piston as the propelling means for the spear presents several unique problems, the piston, upon release from the triggering means, travels forward with high velocity in order to drive the spear or harpoon out of the barrel. The effective performance of this function requires that the piston must do the following: it must be capable of restraining the spear from falling out of the barrel due to gravity; it must have efficient means for deceleration or shock absorption at the termination of its travel, and it must be capable of sealing compressed air up to 600 p.s.i. The impact of the piston, upon reaching the stop means at the muzzle, creates a sharp sound which is clearly audible for some distance under water. It has been observed that in certain underwater areas, particularly where spear-fishing activity has been extensive, this sound may tend to make the fish rather wary and difficult to approach. Although these limitations can be overcome to a great degree, as will be shown in the present invention, a single purpose spear gun of this type may be a handicap to the user.

On the other hand, the hydro-pneumatic spear gun is relatively silent in operation, even when the gas filled accumulator is of the piston-type. The reason for this is that the piston need only travel a short distance and at a relatively low rate of speed in order to purge the column of water which is used to drive the spear from the barrel. Further, the water in the system, serves to cushion the piston, at its termination of travel. Another advantage in the hydro-pneumatic type gun is that there is no need to retain the spear in a piston, as the rear end of the spear can be mechanically detained by the triggering device. For this reason it is to be noted that many skin diving clubs and organizations are strongly opposed to loading or carrying loaded spear guns on or near public beaches. With the hydro-pneumatic gun, this possibility is minimized due to the necessity of filling the barrel with water in order to facilitate loading. The main disadvantage to the hydro-pneumatic gun is that for a given average firing force, the final loading force must be higher than that of a pneumatic spear gun. This is main-

2

ly due to loss of power caused by friction of water flowing through the system. Therefore, when maximum power, with minimum loading effort, is desired, the pneumatic spear gun has decided advantage. In view of the foregoing, it is evident that a spear gun with combined facility for utilizing either the pneumatic or the hydro-pneumatic principle of operation and which can be adapted to either principle, by the user, is highly desirable.

10 It is an object of this invention to provide an underwater spear gun which is compatible to both pneumatic and hydro-pneumatic principles of operation. It is a further object of this invention to provide a spear gun which may be used with a minimum of adjustment in either the purely pneumatic or in a hydro-pneumatic form of operation.

Another object of the invention resides in the provision of an improved spear gun utilizing a sealed compressed air supply with provisions for external pumping means.

20 Still another object of the invention resides in the provision for an air operated improved trigger safety device.

A still further object of the invention resides in the provision for a one-piece, opposing pressures operated, trigger coupled, spear and piston latching device.

25 A still further object of the invention resides in the provision for an improved air propelled dual piston with air operated deceleration means.

A still further object of the invention resides in the provision of an improved spear gun utilizing a muzzle assembly with air-operated shock absorbing means.

30 A still further object of the invention resides in the provision of an improved spear and spear retrieving collar.

35 It is a still further object of this invention to provide an underwater spear gun of moderate cost, easy to use, light in weight, reliable, extremely powerful, accurate and well balanced. The gun of this invention is intended to be readily adjustable so that loading forces can be varied as desired by the user.

40 In the attainment of these and other objects as found in the present invention, in one embodiment I provide a gun of hydro-pneumatic operation and having a firing tube carried by a handgrip. This tube is adapted to receive the shank end of a spear having a shaped end adapted to act as a piston—this end also having a detent means adapted to be engaged and released by a trigger mechanism carried by the handgrip. Said trigger mechanism having a safety device for preventing the unintentional release of an armed gun. In yet another embodiment I provide a gun adapted for pneumatic operation and similar in most respects to the gun of hydro-pneumatic operation except that the firing tube has a nose-piece or check member to retain a movable piston slideable in the bore of the firing tube.

45 55 In still another embodiment of my invention I provide a gun readily convertible from pneumatic to hydro-pneumatic operation and back again. This convertible gun is similar in most respects to the guns above, however, there is provided a novel valve for permitting the rear or internal portion of the firing tube to be opened to a pneumatic spring assisted chamber. A novel pneumatic cushion is also shown in conjunction with this embodiment.

60 65 In the accompanying drawings is shown the spear gun in the various embodiments as outlined above. In one embodiment the gun is arranged to be used in a hydro-pneumatic manner while in another embodiment the gun is arranged to be used in a pneumatic manner. In yet another embodiment is shown the spear gun arranged to be used as a pneumatic gun and with the same components to be readily convertible by rearrangement

of certain members into a hydro-pneumatic gun and readily reconvertible into a pneumatic gun.

It is understood that the drawings are illustrative of the invention rather than limiting the invention.

In the drawings:

FIGURE 1 represents a side view showing the general arrangement of the gun and spear and particularly when arranged for hydro-pneumatic use;

FIG. 2 represents a longitudinal view, mainly in section and in enlarged scale, of the spear and gun of FIG. 1;

FIG. 3 represents a sectional view taken on the line 3—3 of FIG. 2 and showing the trigger mechanism for holding the spear in armed position;

FIG. 4 represents a side view of a spear gun similar to the gun of FIG. 1 but with a gun arranged for pneumatic use;

FIG. 5 represents a longitudinal view, mainly in section and in enlarged scale, of the spear and gun of FIG. 4;

FIG. 6 represents a sectional view taken on the line 6—6 of FIG. 5 and showing the trigger mechanism with the safety mechanism in a different position than in the view of FIG. 3 and with the spear in armed position;

FIG. 7 represents a sectional view of a handle portion taken on the line 7—7 of FIG. 5;

FIG. 8 represents a sectional view of a handle portion taken on the line 8—8 of FIG. 2;

FIG. 9 represents a sectional view taken on the line 9—9 of FIG. 14;

FIG. 10 represents a cross sectional view of a muzzle portion of another embodiment of a gun in pneumatic arrangement and showing the piston and firing tube and with the spear and retrieving ring at the moment the piston arrives at the end of its travel;

FIG. 11 represents a sectional view similar to FIG. 10 but showing the piston just prior to its reaching the end of its travel;

FIG. 12 represents a sectional view of a muzzle portion of yet another embodiment of a gun of hydro-pneumatic form and showing the spear and retrieving ring of FIG. 10 as adapted to this embodiment;

FIG. 13 represents a cross sectional view of the retrieving slide of FIG. 9 and showing the slide members prior to the assembly thereof;

FIG. 14 represents a modification of the gun of FIG. 5 in which the spear and retrieving ring of FIG. 10 and a valve check is added to the muzzle of the gun of FIG. 5;

FIG. 15 represents a sectional view similar to FIGS. 2 and 5 and showing another embodiment of a gun adapted to be used in either a pneumatic or hydro-pneumatic manner and with the muzzle adapted for hydro-pneumatic use;

FIG. 16 represents a sectional view of the muzzle of the gun of FIG. 15 with the gun converted for pneumatic use; and

FIG. 17 represents a sectional view of yet another embodiment of a muzzle adapted for use as a pneumatic gun.

Referring now more particularly to the drawings in which like numbers refer to like members, the hydro-pneumatic gun and spear exemplified by FIGS. 1 through 3 include a handgrip 1 which is preferably made of a high impact plastic, and which is so formed as to provide a trigger housing. A firing tube 2 is carried by the handgrip 1, said tube being threaded at the handgrip end and screwed into a threaded opening 2a provided in the handgrip and sealed therein by means of an O-ring 3. The firing tube 2 is a long, smooth bored tube of generally the same diameter and having the muzzle end formed with a reduced external outer portion of relatively short length and then an external threaded portion 2b adapted to receive the internally threaded portion of a flanged adapter 4. This adapter 4 is addition-

ally provided with a larger threaded bore portion 4a into which is screwed the externally threaded portion of a nose section 5. Nose section 5 is further formed with a concentrically tapered bore 5a. A spear retrieving slide 6 has a portion thereof formed into a concentric conical rear section 6a which mates with and is seated in bore 5a. In addition to providing a connection to the spear, retrieving slide 6 has a bore therein adapted to center the spear 21 in the firing tube in order to provide maximum accuracy of the spear during its flight after being released from the gun. A description of the operation of the slide in the retrieving of the spear will appear below in connection with the description of the operation of the gun. As seen in FIG. 2, the rear end of handgrip 1 is formed with an external thread 1a with which to receive an internally threaded end of a tube 7 which forms the outer wall of a compression chamber. An O-ring 8 is fitted into a recess adjacent thread 1a and provides a seal of the threaded joint of tube 7 and handgrip 1. A tapered passageway 9 extends from the interior end of firing tube 2 through the handgrip and to its end this opening joining the interior chamber of tube 7. The interior of tube 7 forms an air accumulation chamber 7a which carries a slidable piston 10 which has an O-ring 11 acting as a piston ring. Shoulder 1b formed of the end wall of handgrip 1 provides a stop means for the forward motion of piston 10. The piston 10 has a relief 10a formed therein in order to reduce its mass or weight. Tube 7 has its unattached end internally threaded at 7b which thread receives and retains a check valve retainer 12. An O-ring 13 carried in a groove adjacent the external threaded portion of retainer 12 provides a sealing means between tube 7 and retainer 12. A check valve 14 as conventionally used in tire stems or tire tubes is threadedly carried by an internal threaded recess 14a in valve retainer 12. An O-ring 15 may be used to seal the check valve 14 in recess 14a. A threaded plug 16 is mounted in an enlarged internal threaded recess 16a at the rear end of retainer 12 and is sealed therein by means of an O-ring 17. A formed wire loop or catch 18 is pivotally mounted in opposed blind holes in plug 16 and is conventionally used to facilitate the attachment of a securing line from the gun to a towable float.

The loop also serves as a tool with which to turn plug 16 so as to remove the plug from the retainer 12 so that an air pump (not shown) of the conventional hand operated tire pump type may be employed to charge compressed air into chamber 7a, the check valve 14 acting in a conventional manner to retain the air forced into the chamber 7a. A combination balance and inertia damping weight 19, preferably made of lead, is disposed at the rear of and within tube 7. An air passage 19a in weight 19 provides a passageway for air to be admitted into the air chamber through check valve 14. A screw 20 carried by weight 19 enters retainer 12 and secures weight 19 to retainer 12. Of note is weight 19 which provides a balance for the mass of the spear 21 when it is mounted in the barrel of the gun. This providing of a balance permits the gun to be used with one hand, leaving the other hand free for swimming or other purposes. The balance weight also aids in absorbing the reactionary forces imposed when firing the gun and thus improves the accuracy of the spear as it is fired from the barrel of the gun.

A spear 21 as seen in FIGS. 1 and 2 is disposed in the gun in an armed position in tube 2. In this position the retrieving slide 6 is disposed just to the rear of a spear point 22 which may be attached to spear 21 by means of a threaded portion of the spear point which is screwed into a threaded recess 21a of the spear. A fuller description of slide 6 and alternate embodiments appear later in the description. A conical section 6a of retrieving ring 6 is adapted to seat and be tightly held by a tapered bore 5a formed in the nosepiece 5.

A retrieving cord 23 extends from a yieldable hooklike member 24 which is mounted upon or is positioned around the rear portion of tube 7. This hook is conventionally made of rubber or of a flexible plastic. This hook member 24 engages the cord at about its middle and one portion 23a of the cord extends forward and is threaded through a hole 25 in the flange of adapter 4 and is secured thereto. The other end 23b of the cord is brought forward from hook 24 and secured to a shorter cord 26 which is threaded at both ends through a pair of holes 27 in the ears of retrieving slide 6. The rubber hook 24 provides a sufficient bias to maintain the retrieving cord 23 in a taut condition.

The spear 21 conventionally has a long cylindrical shank portion which is slidable in the bore of slide 6 with the point and the threadedly engaged portion 21a extending beyond the slide 6. The rear end of the spear 21 has formed therein a threaded recess 21b which receives and retains a short, cylindrical, spear adapter 28 having a diameter slidable in the bore of tube 2. In this diameter is provided an annular groove for O-ring 29 which acts as a piston ring for adapted 28 and which acts as a gas or fluid seal in the bore 2c of firing tube 2. An annular flange 28a is formed at the rear of the adapter 28.

The trigger mechanism is retained in handgrip 1 and as seen in FIGS. 2 and 3 is illustrated in the armed position. A cylindrical latch 30 is slidably carried in a vertical diametral recess 1c and reduced diametral recess 1d of handgrip 1. This latch lies between passage 9 and the end 2a of tube 2 and is provided with a transverse bore 30a which connects these two passages. This bore 30a is tapered at the forward end and is identified 30b while the rear of the bore is recessed as 30c and forms a latching shoulder for engagement with annular flange 28a of the adapter 28. An O-ring seal 31 is carried in an annular groove in the larger diameter portion of latch 30 while an O-ring seal 32 is also carried in an annular groove in the smaller diameter portion of latch 30. Seals 31 and 32 prevent flow to and from the outside of the gun to the passageway extending from 9 to tube 2 and also impose an urging force in the upward or latching direction on latch member 30. This force is provided by the internal water pressure reacting on the greater annular area of seal 31 as opposed to the lesser annular area of seal 32 when the gun is in the armed condition. Unlike conventional guns this principle foregoes the necessity of a mechanical spring to return the latch to the latching position. The lower end of the latch 30 is a reduced portion and has a slot 33 transversely formed to the axis of the latch. A pin 34 is slidable in this slot and engages a trigger member 35 in a slot 35a. The member 35 is pivotally retained by a pin 36 which is rotatable in the hole formed in the member 35. The pin is non-rotatably secured in a transversely disposed hole in reduced portion 41 of handgrip 1.

The safety mechanism associated with the trigger mechanism described above is illustrated in FIGS. 2, 3, 5, 6 and 7, and includes a piston 37 having a spherically formed left or forward end and having an annular groove at the opposite end adapted to seat therein an O-ring 38. A safety member 39 is slidably and pivotally retained in recess 40 formed in the handle portion of handgrip 1. A blind hole 39a in member 39 provides a bore for the insertion and movement of piston 37 which as it is inserted into the hole 39a forms a miniature pressure chamber as the atmospheric air trapped therein is compressed by the inward movement of the piston 37. This reactionary force on piston 37 urges it forwardly against the rear of trigger member 35 which engages pin 34 to urge latch 30 upwardly into latching position. This contained pressure urging piston 37 forwardly causes member 39 to be preloaded toward the off position as best seen in FIGS. 5 and 7. Trigger

member 35 is locked in the safety condition by manipulation of lug 39b which is urged to the left or forward with the thumb of the hand holding the gun (projecting lug 39b of safety member 39 may be arranged to accommodate either left or right hand operation) until the rear of the projection 39b is displaced from slot 42 formed in the handgrip 1. The projection is then rotated to a downward position as illustrated in FIGS. 2, 3 and 8. This lug 39b now becomes a rigid member disposed between the rear of trigger 35 and surface 43 of handgrip surface 43 acting as a shoulder stop 1 thereby preventing an accidental actuation of trigger 35. The volume of air in pressure chamber 39a is thus further reduced by the forward movement of member 39 causing a greater pressure in this chamber, further urging trigger 35 forward. It is to be noted that plunger 37 could be urged forwardly by means of a compression spring rather than a pressure chamber. Such a spring (not shown) would preferably be made of a metal that would resist rust and corrosion likely to develop because of exposure to salt and/or fresh water. To deactivate the safety device, the lug 39b is rotated upwardly to engage slot 42 whereupon the compressed air in chamber 39a urges the lug rearwardly into the slot. A bleed passage 40a is provided from the rear of bore 40 to the exterior of handgrip 1 so that any trapped water or air behind the moving member 39 will not be trapped in the bore 40 but will be purged therefrom.

Operation of gun in hydro-pneumatic form

To operate the gun of FIGS. 1 through 3 the following procedure is preferably followed: the air in chamber 7a is brought to the desired pressure by the admitting of compressed air through the check valve 14 while plug 16 is removed from the handgrip. Plug 16 is then reinserted into the retainer 12. The gun is then submerged to allow the barrel to be filled with water which completely fills bore 2c, transverse bore 30a and hollow passage 9. Adapter 28 is inserted into the nose section 5. Slide 6 is mounted in the tapered portion 5a and then the gun is armed by manually forcing the spear through the barrel toward the rear of the gun. A loading device of conventional construction (not shown) is usually used to assist in inserting the spear. O-ring 29 acts as a seal to prevent the water in the barrel from leaking past the spear with the rearwardly urged water forcing the piston 10 rearwardly to compress the air in chamber 7a. The spear is pushed into the gun until the annular flange 28a of the adapter 28 passes through bore 30a of latch 30 and the flange is engaged by the shoulder of the latch 30 and takes the armed position as shown in FIG. 2. Safety 39 is manipulated so that lug 39b is in the downward position as described above and with the safety activated the cord 23 is stretched over yieldable hook member 24 and held thereon. To fire the gun, the safety device 39 is first released by turning lug 39b upwardly, usually with the thumb of the hand holding the gun, thence squeezing or pulling the trigger 35 with the forefinger of the grasping hand. The trigger, when pulled, causes pin 34 to be moved downwardly simultaneously moving member 30 downwardly so as to cause the shoulder of member 30 to disengage from flange 28a. The spear assembly now released is free to move through the barrel whereupon the compressed air in chamber 7a moves the piston 10 toward the spear 21 forcing the trapped water between the end of the adapter 28 and the piston 10 to move forwardly to eject the spear from the barrel. Prior to leaving the barrel, the rear adapter 28 of the spear 21 engages retrieving slide 6 and urges the slide from its seat in nose piece 5. The slide 6 attached to cord 26 thence to cord 23, is carried by the movement of the spear to cause the cord 23 to tighten forcing it to pull away from yieldable hook 24. The spear, now completely free of the gun, travels until it hits its mark or until the cord 23 is pulled to its limit. The spear is retrieved by pulling the cord 23 toward the gun. As

there is no loss of air on firing of the gun, the spear may be reloaded and fired repeatedly without the necessity of recharging the air chamber 7a.

Pneumatic gun

The guns of FIGS. 1-3 adapted to be changed from a hydro-pneumatic gun to a pneumatic gun with an interchange of relatively few parts. Those parts that are like parts carry like numbers and function in like manner and in FIGS. 4 through 6 illustrate an embodiment that is arranged to operate as a pneumatic spear gun. In FIG. 5 it is noted that piston 10 is not present in the chamber 7a and may be removed by unscrewing retainer 12 from tube 7 and pushing piston 10 from the chamber. The retainer 12 is then reassembled forming a larger chamber 7a and providing a free passage of air from chamber 7a through passage 9 thence through bore 30a and finally through the bore 2c of the tube 2. Slidably disposed within and completely closing the bore 2c of the firing tube 2 is a piston 44 which is similar in shape to the adapter 28 discussed above. This piston 44 is provided with an annular groove which retains an O-ring 45 which acts as a piston sealing ring for piston 44 and tube 2. The rear end of this piston is formed with an annular flange 44a which forms a latching shoulder similar to shoulder 28a. This flange 44a is retained and engages latch 30 as described above. In the recess 21b of spear 21 is a tailpiece 46 which is threadedly mounted therein. A shouldered portion 46a, which when mounted lies adjacent the end of spear 21, is of a slightly larger diameter than the shank of the spear. The rear portion of tailpiece 46 is formed with a conical portion 46b which is adapted to be held in a cone seat 44b formed in the forward portion of piston 44. The conical portion and seat is similar to the conventional taper lock as used on machine tools, and providing sufficient restraint when assembled to prevent the spear from falling out of the piston from a force such as gravity, but light enough to allow ready separation upon the firing of the gun. The forward or muzzle end of the tube 2 is provided with a nosepiece 47 which is externally threaded so as to be mounted in thread 4a in adapter 4 after nose 5 is removed therefrom. This nosepiece is formed at its forward end with a concentrically bored hole 47a and a concentric counterbore 47b in its rear portion. An annular internal recess is provided within bore 47a for the mounting and retaining of an O-ring 48. A piston member 49 is slidable within nosepiece 47. The O-ring 48 provides a slidable seal between nosepiece 47 and a similar external diameter 49b of piston 49. A larger diameter 49b is formed at the rearward end of the piston and a groove is provided therein for the retention of an O-ring 50 which acts as a seal between surfaces 47b and 49b. Piston member 49 is also formed with a concentric bore 49c adapted to slide freely on the shank of the spear 21 and with a concentric taper 49d at the forward end which taper is adapted to receive the conical section 6a of retrieving slide 6. Nosepiece 47 and piston 49 combine with the seals as outlined above to provide a shock absorbing muzzle assembly.

The assembly and operation of this shock absorbing muzzle unit is as follows: piston 49 with an O-ring 50 mounted thereon is inserted into nosepiece 47 having an O-ring 48 mounted therein. With small diameter 49a inserted in bore 47a the nosepiece 47 is threaded into recess 4a until seated as in FIG. 5. As thus assembled an annular recess 51 is formed with seals 48 and 50 acting to retain the air that is trapped therein during assembly. Recess 51 thus becomes a small compressed air chamber. When desired, a small check valve 52 of the conventional tire tube type and mounted as illustrated in FIG. 14 may be used to provide a passageway through which may be added compressed air. The concentric bore 49c of piston 49 is of a diameter to permit the free passage of the shank of the spear but is smaller than the bore 2c of the firing tube so that the piston 44 as it moves forwardly in

the barrel engages and is stopped by the inward shoulder of the piston 49.

Operation of gun in pneumatic form

5 The pneumatic form of the gun as in FIGS. 4-7 provides that the air chamber 7a as well as the barrel portion behind barrel piston 44 be charged with compressed air through the check valve 14 and in the manner described for the hydro-pneumatic gun. The spear 21 with retrieving ring 6 thereon is inserted into the open end of the muzzle with the tapered portion 6a seated in the concentric taper 49d of piston 49. Tailpiece 46 is now inserted through the open end of the muzzle piston 49 and is seated into cone seat 44b of barrel piston 44. The gun 10 is armed or cocked by manually forcing the spear through the barrel toward the rear of the gun and usually there is utilized a loading device of the conventional type as is used to load conventional spring guns. The piston seal provided by O-ring 45 prevents the compressed air in the barrel from leaking past the piston 44 thus the air in the gun is further compressed as the spear is forced through the barrel. As the piston is pushed down the barrel the rear annual flange 44a of the piston passes through bore 30a of latching device 30 and engages the latching shoulder 20 as described above. The safety device is manipulated as described in the hydro-pneumatic gun and is fired in the same manner. The cord 23 is stretched as described above and when the gun is fired the latching member 30 disengages from flange 44a and piston 44 is released to rush forwardly as urged by the compressed air in chamber 7a. The movement of the piston pushes the spear forward at high velocity. The piston is decelerated by means of the shock absorbing muzzle unit in which piston 44 as it reaches the muzzle engages the piston 49 and forces this piston forward. As this piston 49 moves forward it compresses the air in chamber 51 until sufficient pressure is built up to stop the forward motion of the barrel piston 44. The rather abrupt stop of the piston 44 causes spear tailpiece 46 to disengage from the tapered bore 44b and to pass through the bore 49c of the piston. It is to be noted that the slide 6 at the muzzle and the piston 44 in the bore of the tube 2 serve to accurately guide the spear. As it leaves the muzzle the spear tailpiece 46 engages the retrieving slide 6 and, as above, pulls the slide, the cord 23 and the bridle cord 26 with it as it leaves the gun. The spear travels and is retrieved as in the hydro-pneumatic gun above. As in the hydro-pneumatic arrangement there is no loss of air in the pneumatic arrangement and the spear may be reloaded and fired repeatedly without the necessity of recharging the air chamber.

45 In the use of pneumatic type spear guns it is to be noted that the spear propelling member, or piston which is used to eject the spear from the barrel, is subjected to very high impact and deceleration stresses which are, in turn, transmitted to the muzzle, or stop means members of the gun. In the conventional pneumatic spear guns, various deceleration means such as a mechanical spring incorporated in the muzzle or rubber washers attached to the piston have been utilized for shock absorption. Springs, however, are subject to deterioration and breakage due to the corrosive action of sea water. Rubber washers are subject to deterioration, splitting, permanent deformation and add unnecessary weight to the piston 50 creating a greater mass which must be decelerated. The improved, air operated piston shock absorbing muzzle described in connection with FIG. 5 obviates the limitations of these prior devices.

An alternate dual piston assembly as illustrated in FIG. 70 provides another form of air operated piston shock absorbing muzzle for use on pneumatic type spear guns. A piston assembly 53 includes a driving piston 54 and a deceleration piston 55 of tubular shape. The driving piston 54 has its rear portion shaped with an annular flange 54a which forms a latching shoulder for engage-

ment with latch 30 described above. A diametral recess 54b which is provided to reduce weight and is formed in the rear of the piston 54 connects with a smaller air passage 56. Forward of and connecting with recess 56 is a concentric bore of a larger diameter which terminates in a still larger diameter provided with internal threads. A transverse hole 57 formed in the wall of piston 53 is disposed adjacent the forward end of recess 56 and acts as an orifice for the passage of air into and out of the enlarged inner recess. An O-ring 58 is mounted in an annular groove in the external surface of an enlarged rear portion of piston 54. This O-ring acts as a piston ring to seal the piston 54 within the tube bore 2c. A conical valve seat 59 is provided at the junction of the larger bore and air passage 56 and the orifice 57. Deceleration piston 55 is provided with an external groove within which is mounted an O-ring 61 which acts as a piston ring between the piston and tube bore 2c while in the same piston an internal groove is also provided for the mounting therein of an O-ring 62 which acts as a piston ring seal between piston 55 and a forward reduced external diameter 54c of piston 54. Mounted in the larger internal bore portion of piston 54 is a cylindrically shaped needle valve member having a conical inner end adapted to engage and provide a sealing means with the valve seat 59. The left or enlarged end of the valve is formed with an external thread 63a to threadedly engage and be manipulately mounted to the threaded forward portion of the enlarged recess of piston 54. Inwardly of the threaded portion of the needle valve 63 there is formed in the reduced shank portion an annular groove adapted to receive an O-ring 64 which provides a seal for the bore portion of the piston 54 which carries the needle valve. The external forward end of the piston portion 54c is formed with a taper 54d which is preferably a locking taper adapted to engage a tapered recess 66a of a spear 66. Adjacent taper 54d there is formed in reduced diameter 54c a groove adapted to engage and hold a snap or retaining ring 69 which forms a forward stop or shoulder for the retention of the piston 55 on the diameter 54c. Muzzle stop member 65 of generally tubular shape is formed with an internally threaded portion adapted to be threadedly mounted on the forward end of tube 2. A reduced concentric bore 65a is formed at the forward end of member 65, said bore slidably receiving the shaft portion of spear 66. A shoulder 65b extending between the two different sizes of bores provides a stop means for the forward motion of the piston assembly 53. An external annular flange 65c is formed on stop 65, said flange having transversely drilled holes 65d through which is secured retrieving cable 23. Stop member 65 is formed at its forward end with an external taper upon which is mounted a spear retrieving slide 67 to be more fully described later. The cord 26 is fastened to slide 67 and the operation is similar to the operation described above.

The operation of the dual piston assembly 53 of FIGS. 10 and 11 is as follows: Prior to charging the gun with compressed air the needle valve member 63 of driving piston 54 is screwed outwardly two or three turns so as to permit the flow of air through the air passage 56, thence through orifice 57 and into air chamber 70. Air chamber 70 consists of the volumetric area surrounding the reduced diameter 54c and is disposed between the rear face of deceleration piston 55 and the forward face of driving piston 54 and is enclosed by the wall of tube 2. The gun is charged with compressed air. As the pressure is increased within the air chamber 7a and the barrel 2c, it is similarly increased within the air chamber 70 of the piston assembly. When the desired internal pressure is reached, the needle valve member 63 is screwed inwardly to close off the conical valve seat 59 thus forming the pressurized slidable piston assembly 53. The tailpiece of the spear 66 is now inserted into the open end of muzzle member 65 and is mounted on the tapered projection 54d of the driving piston 54. The gun is now

ready to be cocked and fired in the manner previously prescribed in connection with FIG. 5. In FIG. 11 is shown the piston assembly just prior to reaching the stop shoulder 65b of the muzzle member 65 and it is to be noted that the spear shoulder 66d has not yet reached the retrieving slide 67. In FIG. 10 the piston, spear, and slide are shown at the moment the deceleration piston 55 contacts the stop shoulder 65b of the muzzle 65. It is to be noted that the tapered portion 66c of the spear 66 has reached the slide 67. As the deceleration piston 55 is stopped by the muzzle member 65, the driving piston 54 continues to move forward thereby further increasing the pressure in the air chamber 70 until the internal pressure therein decelerates and stops the forward movement of the driving piston. The forward moving spear 66 then pulls free of the driving piston and the slide 67 with bridle 26 and cable 23 is carried by the spear as it emerges from the muzzle.

FIG. 12 also shows the hydro-pneumatic gun of FIGS. 1 and 2 but with the muzzle section altered to utilize the spear 66 and retrieving slide 67 of the pneumatic embodiment shown in FIG. 10. In FIG. 12, the spear adapter 71 is slidably disposed to the rear of spear 66 and threadably secured in the threaded recess 66b thereof. It will be noted that, with the exception of the tapered threaded forward section 71a the adapter 71 is identical to the spear adapter 28 of FIG. 2 and previously described. An O-ring seal 72 carried in a groove in adapter 71 acts as a piston ring to seal the adapter 71 in the bore 2c of the firing tube 2. Except for the slightly enlarged bore 73a which is formed as a continuation of the outer end of the bore 2c, the muzzle nosepiece member 73 is identical to the muzzle member 65 of the embodiment shown in FIG. 10 and previously described. The rear, reduced radius portions of the retrieving slide 67 are slidably disposed within bore 73a of the muzzle nosepiece 73 and serve to center the spear in the barrel. The gun is cocked and fired in the same manner as the gun previously described and illustrated in FIGS. 1 and 2.

FIG. 14 illustrates the embodiment of the muzzle and barrel piston of the gun of FIG. 5, however a modified muzzle piston 74, spear 75 and tailpiece 76 are used to utilize the retrieving slide of 67. Except for the reduced diameter 76a which is slightly smaller than the diameter of the spear, the spear tailpiece 76 is identical to the tailpiece 46 of the gun shown in FIG. 5. Muzzle piston 74 is similar to muzzle piston 49 (FIG. 5) but is provided with a reduced internal diameter 74a which is slightly larger than the diameter of the spear 75 and provides a sliding fit between spear and diameter 74a. Spear 75 is similar to the spear 21 of FIG. 5 except that an external tapered portion 75a is provided forward of tailpiece 76 to form a stop shoulder 75b for the engagement thereby of retrieving slide 67. The manner of operation of the gun is similar to the gun of FIG. 5.

The conventional spear retrieving slide is usually provided with a bored hole of substantially the same diameter as the spear shaft and is slidable thereon. The tailpiece, or rear of the spear, is usually provided with a slightly larger diameter than the spear shank in order that the shoulder provided by this larger rear piece will engage or catch the retrieving slide upon leaving the barrel. Although this method as described is effective, difficulty is often encountered in the passing of the large diameter tailpiece through the muzzle of the gun without impinging some part of the muzzle. This impingement can cause the spear to be deflected from its line of flight and seriously affect its accuracy. The probability of impingement has been overcome in the present invention by the utilization of the tapered rear section 6a as described in conjunction with and shown in FIGS. 2 and 5. This tapered rear section insures that the rear of the spear is centered in the bore and in the muzzle as it is ejected. In addition to the method as used in FIGS. 2 and 5 there is another approach to this problem and in this connec-

tion the tailpiece is made the same diameter or smaller than the shank of the spear. This reduced size provides for the elimination of any shoulders or protrusions which may impinge on the muzzle.

The embodiment showing a reduced diameter tailpiece is shown in FIG. 10 and includes a spear 66 which is similar in all respects to the spear illustrated in FIGS. 2 and 5. The tailpiece of this spear 66 is preferably an integral part of the spear and is provided with an internal tapered recess 66a which is adapted to accept the conical taper 54d of the driving piston 54. The forward end of the tapered recess 66a is provided with an internal thread 66b in which is threadedly mounted the tailpiece adapter 71 of the hydro-pneumatic embodiment of FIG. 12 described above. Just forward of the thread 66b the external diameter of the spear is provided with a conically tapered portion 66c terminating at the smaller end in a shoulder portion 66d. Mating with taper 66c and terminating at shoulder 66d is retrieving slide 67. FIG. 9 shows a frontal view of this slide 67 with a fragmentary portion in section to illustrate the method of assembly. This slide 67 is essentially comprised of two similar halves 67a preferably made of steel and which, when assembled, form the slide member 67, the assembly being pivotally and slidably disposed about the spear shaft 66. Each member 67a is formed with a tapered semi-tubular rearward portion and with a larger external radial portion forwardly thereof which radial portion is provided with a radial groove or recess adapted to accept an elastic band 68. The forward end of the slide member 67a is provided with a small diameter pin projection 67b and with a hole of slightly larger diameter 67c diametrically opposite thereto and a transversely extending ear provided with a hole 67d to accept one end of the bridle 26 which is knotted and secured thereto. FIG. 13 illustrates the members 67a just prior to assembly in which it is noted that by engaging the pins 67b with their respective matching holes 67c the completed assembly will provide an internal diameter which is free to slide over spear shaft 66. It is to be further noted that when the members 67a are assembled as in FIGS. 9 and 14 the slide assembly 67 will be a mating fit with the shaft and the elastic band 68 when mounted in the groove adjacent the ear portions will urge the members 67a about the spear shaft 66. When the spear has been fired, the shaft will move forwardly in the barrel and slide assembly 67 and upon reaching the slide 67 the taper 66c of the spear will allow the rear portions of the two halves to move inwardly toward each other and as urged by the elastic band 68 to close about the taper 66c and engage the spear shoulder 66d. Thus engaged the slide 67 will be carried by the spear 66 as it leaves the gun.

Convertible hydro-pneumatic, pneumatic spear gun

An embodiment of a convertible spear gun adapted to be changed from and to a hydro-pneumatic method and from and to a pneumatic method is shown in FIGS. 15 and 16. This gun uses nearly all the components seen in FIG. 5 and those not identical are similar in shape and function and are adapted for the conversion to be described. This convertible gun includes a handgrip 111 similar to handgrip 1 except that a recess 112 is formed in the grip portion. Tube 2 is mounted on the handgrip 111 in the manner of FIG. 5 and carries a spear 21 having a point 22 mounted thereon. A threaded recess 21b described in conjunction with FIG. 5 carries a shouldered stud 80 having an engaging collar 81 formed thereon. A shaped end 82 of reduced size may be in the form of a square, hex or screwdriver point and extends beyond collar 81. A screw plug 83 having a recess in its outer or left end and adapted to receive and be driven by the shaped end 82 is threadedly mounted in a piston 84. A rear tube 7 forming the outer wall of a compression chamber has its rear end closed by a valve retainer 12 and O-ring 13. Check valve 14, O-ring 15, plug 16,

O-ring 17 and loop 18 are mounted in and function in retainer 12 the same as previously described. A compression spring 85 lies adjacent the inner wall of tube 7 and serves a dual purpose. When in the expanded position of FIG. 16 the ends of the spring engage retainer 12 and piston 84 and urge piston 84 forwardly against handgrip end 86. In the bore of piston 84 there is a counterbore portion 87 adapted to rotatably receive and retain a larger outside diameter of the screw plug 83. An O-ring 88 is mounted in an annular recess formed in the bore 87 of the piston 84. A cross-bore and bleeder passageway 90 is formed from the inner end and extends forwardly to terminate at the bore 87. A threaded portion 92 of the plug 83 has a radial external groove formed near its inner end, said groove having mounted therein a snap or retaining ring 94 which provides a stop for the outward screwing of the plug 83.

In form the gun of FIG. 15 is arranged to be used as a hydro-pneumatic gun, the nosepiece assembly 47 is removed from flanged adapter 4 and is stored in the recess 112. As shown, the tapered muzzle portion of the nosepiece is mounted on a rubber button or shoulder piece 96. The threaded end of the nosepiece is held in place by a rubber plug 98 having a spherical end adapted to engage the inner edge of the threaded end. The resilience of the spherical end of the plug permits the nosepiece to be snapped into and out of the recess 112. In hydro-pneumatic operation the screw plug is turned all the way inwardly by manipulation of the spear 21 and by using barb 99 as a wrench handle to turn the shaped end 82 and engage screw plug 83.

A spear piston piece or plunger 100 as seen in FIG. 16 includes a centrally formed diametral recess adapted to receive the reduced portion of stud 80 including the collar portion 81 and shaped end 82. The outer portion of the piston 100 has a cylindrical portion slidably in the tube 2 and a reduced portion 101 and an annular flange 102. This shaped end of portion 101 and flange 102 is adapted to engage the latch 30 described above and which is moved in response to the trigger 35. In the larger diameter portion of piston 100 there is formed a groove in which O-ring 103 is seated and acts as a piston ring seal in tube 2. A lateral recess 104 is also formed in the side of the larger diameter and mounted therein is a spring 105 retained there by the head of a screw 106 mounted in a tapped hole in the piston body. Spring 105 has its free end formed with a V-shaped engaging portion arranged to engage collar 81 of stud 80 when the stud is inserted into the piston.

Operation as hydro-pneumatic gun

To use the gun of FIG. 15 as a hydro-pneumatic gun the spear 21 has piston 100 removed from the stud 80 and by means of shaped end 82 the screw plug 83 is turned all the way in to form a compression chamber within tube 7. This chamber is charged with air in the manner described in conjunction with FIG. 2 above. Nosepiece 47 is removed from the adapter 4 and stored in recess 112 in the handgrip 111. Piston 100 is mounted on stud 80 and with the gun barrel or tube 2 filled with water the gun is cocked or armed and then fired in the manner described above in conjunction with FIG. 2.

Operation as pneumatic gun

To use the gun of FIG. 15 as a pneumatic gun the piston 100 is removed from spear 21 and by means of shaped end 82 and barb 99 the spear is rotated so as to engage and turn screw plug 83 outwardly until retaining ring 94 reaches or nearly reaches the inner end of piston 84. After being screwed out so that the larger diameter of the screw plug 83 is outside counter bore 87 the passageway 90 will be open from the compression chamber inside tube 7 and to the tapered passageway 9 within the handgrip 111. Piston 100 is inserted in bore 2c and nosepiece 47 is removed from recess 112 and then is

mounted on adapter 4 as shown in FIG. 16. The chamber 7 and tube 2c is charged with air through check valve 14 in the manner described in conjunction with FIG. 5. The gun is cocked or armed by inserting stud 80 in the recess in piston 100 and pushing piston 100 inwardly until reduced portion 101 and flange 102 engage the latch 30 in the manner described for the guns of FIGS. 2 and 5. When fired the piston 100 is rapidly moved to the muzzle whereupon the forward shoulder of the piston 100 engages the piston 49 of the nosepiece 47 the piston 49 decelerates and stops the piston 100 whereupon the collar 81 acts as a cam to lift and disengage itself from the V-portion of spring 105 and spear 21 is free to move forwardly in the manner of FIG. 5.

In FIG. 17 is shown a simplified shock absorber muzzle for use in the gun when used in pneumatic form. In this embodiment an adapter 120 is formed with a threaded recess 121 with which to engage and be mounted on the threaded portion 2b of tube 2. A reduced bore 122 extends from about midpoint of adapter 120 to the forward end of the adapter. This bore 122 is sized so as to slidably accept a shoulder portion 124 of spear stud 125. A piston 126, slidable in tube 2, has a rear portion shaped with a reduced portion 127 and a flange 128 adapted to engage the latch 30 described above. Within the main cylindrical portion 129 of the piston 126 there is a lateral recess 130 similar to recess 104 and in this recess 130 there is mounted the spring 105 and screw 106 mounted as in FIG. 16. Also in cylindrical portion 129 there are formed two annular grooves within which are mounted O-rings 132 and 133 which act as piston rings when piston 126 is slid in tube 2. A forward portion 134 of this piston has a passageway concentrically located therein and providing a guide and sliding fit for stud 125. The outer diameter of portion 134 is made a few thousandths of an inch smaller than bore 122. In use as a pneumatic gun, the gun arranged as in FIG. 17 will have the stud 125 pushed into piston 126 until the reduced end of the stud is engaged by spring 105 which prevents accidental dislodgement. Shoulder 124 engages the forward end of portion 134 and as the spear is pushed into the tube 2, piston 126 will be pushed inwardly to compress further the air in the compression chamber and flange 128 will be engaged by latch 30. When the gun is fired, the piston 126 will move rapidly forward in tube 2 and the water around the shaft of the spear will be expelled with the spear. When portion 134 enters bore 122 the water trapped by the advancing piston 126 in larger bore 2c must be expelled through this small circular orifice formed by the predetermined clearance between portion 134 and bore 122. Selective clearance between these pieces will provide the desired checking action. As piston 126 is decelerated and stopped the spear travels forwardly with the collar portion on the stud 125 camming the spring 105 out of the way and the stud 125 sliding out of the passageway.

It is to be noted that spring 85 in the compression chamber in addition to acting as a brake on the rotation of piston 84 also acts to provide a propulsive force on the piston 84. When the gun is cocked, piston 84 is moved rearwardly causing spring 85 to be compressed to nearly its shut height and when fired spring 85 will act with the compressed air to urge the piston 84 forward.

I wish it to be understood that the forms of the invention shown and described herewith, are presented as preferred embodiments of the same, and that other forms and constructions within the scope of the claims may be resorted to without departing from the spirit of the invention.

I claim:

1. A hydro-pneumatic spear gun adapted for use in underwater sports and the like, said gun comprising (1) a handgrip having a communicating through passageway and a latchbore transversely disposed to the communicating passageway, (2) a firing tube mounted on said hand-

grip and connecting with the communicating passageway, the tube adapted to be filled with liquid, (3) a spear of conventional shape and having a piston means at its rear end adapted to slide in and seal the bore of the firing tube as the spear is inserted in the tube, the spear also having a latch engaging means provided in its rear portion, (4) a chamber means for compressed air and the like and connected to the communicating passageway and a piston movable in the chamber and responsive to the insertion of the spear in the firing tube to move the piston and to compress further the air in the chamber, (5) a latch means carried in a latch bore and having piston portions of differing diameters and movable by one of the diameter portions of said piston in response to the fluid pressure thereon developed in the barrel by the insertion of the spear in the barrel to move the latch means into spear engaging position, and (6) a trigger means carried by the handgrip and adapted to move the latch member to a disengaging position, whereby when the piston end of the spear is mounted in the firing tube submerged in fluid and is pushed into the tube the fluid in the tube further compresses the air in the compression chamber and urges the latch into the engaging position and when the spear is fully inserted the pressure-actuated latch will engage the latch engaging means on the spear to retain the gun in armed position until the trigger means is activated to move the latch member to release the spear.

2. A spear gun as in claim 1 in which the dual diameter piston portions of the latch member have a fluid sealing means on each diameter and a fluid conducting means from the communicating passageway to a position intermediate the diameter seals.

3. A spear gun as in claim 2 in which the trigger means includes a safety mechanism for limiting the firing actuation movement of the trigger means, said safety mechanism including a movable safety member having a piston receiving bore therein, a lug on the movable safety member adapted to slide in a guideway formed in the handle, the lug movable from the end of the guideway and to a position against a shoulder stop formed in the handle, the stop adapted to hold the lug in a locked position, a piston carried in the piston receiving bore and having one end arranged to engage the trigger means and the other end carried in the bore, a sealing means on the piston adapted to provide a pressure seal as the piston is moved in the bore and means to confine one end of the bore to provide a compression chamber by which the compressed air therein provides a resilient bias which tends to urge the piston out of the bore whereby when the movable safety member is moved forwardly the lug is moved to the end of the guideway whereupon the outer end of the piston will engage the trigger to resiliently urge the trigger into the cocked position and when the lug is moved from the guideway to the stop the compression chamber will provide frictional engagement of the lug to the stop while the forward face of the safety member will provide a secondary positive stop to prevent the trigger from being moved an amount sufficient to move the latch to the firing position.

4. A spear gun as in claim 3 in which the chamber means for compressed air includes a tube having a piston slidably retained therein and the chamber further having air inlet means for charging the chamber and a weight disposed in the chamber to provide a counterbalancing weight to the firing tube and the provide an inertia dampening effect to the reaction of the firing of the gun.

5. A pneumatic spear gun adapted for use in underwater sports and the like, said gun comprising (1) a handgrip having a communicating through passageway and a latch bore transversely disposed to the communicating passageway, (2) a firing tube mounted on the handgrip and connecting with the communicating passageway, (3) a piston slidably in the bore of the firing tube and having a sealing means mounted on the piston to seal the

bore, (4) a nose-piece means mounted on the muzzle end of the firing tube and adapted to engage and limit the outward travel of the firing tube piston as it moves toward the muzzle, (5) a spear of conventional shape and having a piston engaging means at its rear end by which means the spear is releasably retained and aligned in the firing tube, (6) a chamber means for compressed air and the like and connected to the communicating passageway to provide with the piston in the firing tube a chamber whose size varies as the firing tube piston is moved in the tube to vary the air pressure in the chamber, (7) a latch means carried in a latch bore and having piston portions of differing diameters and movable by one of the diameter portions of said piston in response to the fluid pressure thereon developed in the barrel by the insertion of the spear in the barrel to move the latch means into engaging position, (8) a latch engaging means formed on the firing tube piston and adapted to be releasably engaged by the latch member to retain the piston in an armed condition, (9) a trigger means carried by the handgrip and adapted to move the latch member to a disengaging position, whereby when the firing tube piston is engaged by the spear and is pushed down the barrel to latching position the compressed air in the tube and chamber is further compressed and latch member is urged into engaging position to hold the spear and piston in the armed position until the trigger means is activated to move the latch member to release the spear.

6. A spear gun as in claim 5 in which the latch member is a piston having at least two different diameters and an air pressure sealing means on each diameter and an air pressure conducting means from the communicating passageway to a position intermediate the diameter seals.

7. A spear gun as in claim 6 in which the trigger means includes a safety mechanism for limiting the firing actuation movement of the trigger means, said safety mechanism including a movable safety member having a piston receiving bore therein, a camming means on the movable safety member adapted to slide in a guideway formed in the handle, the camming means movable from the end of the guideway and to a position against a shoulder stop formed in the handle, the stop adapted to hold the camming means in a locked position, a piston carried in the piston receiving bore and having one end arranged to engage the trigger means and the other end carried in the bore, a sealing means on the piston adapted to provide a pressure seal as the piston is moved in the bore and means to confine one end of the bore to provide a compression chamber by which the compressed air therein provides a resilient bias which tends to urge the piston out of the bore whereby when the movable safety member is moved forwardly the camming means is moved to the end of the guideway whereupon the outer end of the piston will engage the trigger to resiliently urge the trigger into the cocked position and when the camming means is moved from the guideway to the stop the compression chamber will provide frictional engagement of the cam to the stop while the forward face of the safety member will provide a secondary positive stop to prevent the trigger from being moved an amount sufficient to move the latch to the firing position.

8. A spear gun as in claim 6 in which the nosepiece means for checking the forward motion of the firing tube piston has a shock absorbing mechanism using a pneumatic chamber and includes (1) an outer nosepiece having means for mounting the sleeve on the muzzle end of the barrel and having an inner surface with at least two concentric diameters of different extent, (2) an inner piston member having an outer surface with at least two concentric diameters of different extent, the diameters adapted to mate to slide in the like-sized inner diameters of the outer nosepiece, (3) means for sealing each of the mating diameters as the inner piston member is moved in the bore of the outer nosepiece, (4) a compression chamber formed of the inner surface of the larger bore

5 of the outer nosepiece, the outer surface of the smaller diameter of the inner piston member and the shoulders extending from the larger to the smaller diameters of the respective outer nosepiece and inner piston member, the compression chamber being reduced in volume as the inner piston member is moved to bring the shoulders toward each other, and (5) means to limit the movement of the inner piston member to keep the inner sleeve mounted in and slidable in the bore of the outer nosepiece.

10 9. A spear gun as in claim 8 in which the outer nosepiece is provided with an air inlet means to the compression chamber.

15 10. A spear gun as in claim 6 in which the nosepiece means includes a positive stop for the piston assembly including an outer member slidable in the firing tube bore the member having an inner concentric bore, a sealing means between the member and firing tube, a piston having a piston portion slidable in the firing tube bore and having a sealing means to seal the piston portion in the bore, the piston having a latch engaging portion formed on the piston portion, a reduced forward shank portion on the piston the reduced shank slidable in the inner bore of the firing tube member, a sealing means in the inner bore of the member to seal the piston and member, a stop means adapted to limit the maximum travel of the piston shank in the firing tube and to retain the plunger in the firing tube, the minimum travel limit provided by the end of the firing tube member and the inner shoulder of the piston portion of the piston and closable air inlet means from the firing tube bore through the piston and to the outside of the reduced shank portion at a point normally intermediate the firing tube member and the piston portion of the piston whereby the air inlet means is opened

20 35 the air under pressure in the firing tube is permitted to enter the circumferential chamber formed by the space between the reduced shank portion of the piston and the firing tube and the air inlet is closed to leave this circumferential chamber to act as a pneumatic cushion as the spear is fired and the piston assembly is moved to the nosepiece means.

40 45 11. A spear gun for use in underwater sports and the like, the gun adapted for use as both a hydro-pneumatic and a pneumatic method of operation and having certain members movable and removable for mounting and storage in and on the gun so as to convert the gun from one method to another method of operation, said gun including (1) a handgrip having a communicating through passageway, (2) a firing tube mounted on said handgrip and connecting with the communicating passageway, (3) a chamber means for compressed air and the like and connected to the communicating passageway and provided with an air inlet means for charging the chamber, (4) a piston movable in said chamber, (5) a valve in the chamber piston and adapted to be closed and opened to render the piston responsive and non-responsive to an external pressure applied to the piston, (6) means to remotely manipulate the valve in the chamber piston, (7) a piston movable in the firing tube, (8) a spear having a shank end adapted to engage and be removably retained by the firing tube piston, (9) a trigger means carried by the handgrip and manipulatedly adapted to engage, retain and release the firing tube piston, (10) a nosepiece adapted to be removably mounted on the muzzle of the firing tube and when mounted to provide a stop for the piston, and (11) storage means for retaining the nosepiece in the gun while the nosepiece is removed from the muzzle, whereby when the gun is arranged for pneumatic operation the valve in the chamber piston is opened to permit the compression chamber to freely communicate with the firing tube, the tube piston is placed in the firing tube and the nosepiece is mounted on the tube to provide a muzzle stop for the tube piston as it is fired, and whereby the gun is arranged for hydro-pneumatic operation the nosepiece is removed from the firing tube

and stored in the storage means, the tube piston is removed from the tube and is mounted on the shank end of the spear and the valve in the chamber piston is closed so that the firing tube may be filled with water before inserting the tube piston and spear shank.

12. A spear gun as in claim 11 in which the trigger means includes (1) a latch bore transversely disposed to the communicating passageway in the hand grip, (2) a latch piston having at least two different diameters and a pressure sealing means on each diameter and a pressure-conducting means on each diameter and a pressure-conducting means from the communicating passageway to a position intermediate the diameter-sealing means, and (3) a safety mechanism for limiting the firing actuation movement of the trigger means.

13. A spear gun as in claim 12 in which the safety mechanism includes a movable safety member having a piston receiving bore therein, a lug on the movable safety member adapted to slide in a guideway formed in the handle, the lug movable from the end of the guideway and to a position against a shoulder stop formed in the handle, said shoulder stop adapted to hold the lug in a locked position, a piston carried in the piston receiving bore, biasing means for urging the piston forwardly in the bore, whereby when the movable safety member is moved forwardly the lug is moved to the end of the guideway whereupon the outer end of the piston will engage the trigger to resiliently urge the trigger into the cocked position and when the lug is moved from the guideway to the stop the biasing means will provide frictional engagement of the cam to the stop while the forward face of the safety member will provide a secondary positive stop to prevent the trigger from being moved an amount sufficient to move the latch to the firing position.

14. A spear gun as in claim 13 in which the biasing means urging the safety piston forwardly includes the piston with one end carried in the piston receiving bore of the safety member and with the other end arranged to engage the trigger means, the piston having a sealing means on that portion movable in the bore and adapted to provide a pressure seal as the piston is moved in the bore, and means to confine one end of the bore to provide a compression chamber by which the compressed air therein provides a resilient bias which tends to urge the piston out of the bore.

15. A spear gun as in claim 14 in which the chamber means includes a spring mounted in the chamber and

arranged to engage the piston movable in the chamber and to urge the piston toward one end of the chamber and in which the storage means for the nosepiece comprises a recess in the handgrip with a nosepiece engaging means disposed in the recess in the handgrip.

16. A spear gun as in claim 11 in which the spear has its shank end provided with a portion diminishing in diameter as it approaches the end of the spear, a shoulder portion formed at the end of the diminished portion, a retrieving slide assembly adapted to be mounted on the spear and to be simultaneously seated in the nosepiece, the slide assembly adapted to engage said shoulder portion at the end of the spear as it is fired from the gun, the slide assembly including cable attaching means, a pair of like members pivotally surrounding the spear and held in slidable engagement with the shank of the spear, a biasing means for urging the movement of two shank engaging portions toward each other to provide a shoulder engaging means when the shank portions are moved onto the diminished portion of the shank and in the way of the shoulder on the end of the shank of the spear.

17. A spear gun as in claim 12 in which the nosepiece has a rear portion adapted to be removably mounted on the muzzle of the firing tube and in which a front portion of determinate length has a bore whose diameter is slightly less than the bore of the firing tube, and in which the piston movable in the firing tube has a forward diameter portion of determinate length and whose outer diameter is a few thousandths of an inch less than the front bore portion of the nosepiece so that when the piston is pushed into the nose piece the rear portion of the piston is able to engage and be stopped by the internal shoulder in the nosepiece and the forward bore of the nosepiece and inserted forward piston portion will have a circular clearance each with the other to thereby provide a circular orifice for controlling the rate and duration of the flow of liquid from the barrel as the gun is fired.
